UNITED STATES PATENT OFFICE.

JOHN B. KELLY, OF PORTLAND, OREGON, ASSIGNOR OF ONE-HALF TO
CHARLES L. VAN BUSKIRK, OF LODI, CALIFORNIA.

DESIGN FOR A MAT.

SPECIFICATION forming part of Design No. 31,881, dated November 21, 1899.

Application filed October 21, 1899. Serial No. 734,412. Term of patent 14 years.

To all whom it may concern:

Be it known that I, JOHN B. KELLY, a citizen of the United States, residing at Portland, in the county of Multnomah and State of Oregon, have invented and produced a certain new and original Design for Mats; and I do declare the following to be a full, clear, and exact description of the invention, such as will enable others skilled in the art to which it appertains to make and use the same.

The invention relates to a new and original design for mats; and it consists of a mat of the shape and configuration shown in the accompanying drawings, in which—

Figure 1 is a top plan view, and Fig. 2 is a longitudinal sectional view.

The leading features of the design comprise a strip of sheet material having an elliptical opening *a*, intersected by slits *b*, formed by an inwardly-projecting tongue *c*, at the base of which is a line of perforations *d*.

What I claim is—

The design for a mat as herein shown and described.

In testimony whereof I have hereunto set my hand in presence of two subscribing witnesses.

JOHN B. KELLY.
